UNITED STATES PATENT OFFICE.

ALAN ERNEST LEOFRIC CHORLTON, OF MANCHESTER, ENGLAND.

MEANS FOR REVERSING INTERNAL-COMBUSTION ENGINES.

1,082,068.

Specification of Letters Patent. Patented Dec. 23, 1913.

Application filed March 18, 1913. Serial No. 755,089.

To all whom it may concern:

Be it known that I, ALAN ERNEST LEOFRIC CHORLTON, a subject of the King of Great Britain, residing at Park Works, 5 Newton Heath, Manchester, in the county of Lancaster, England, have invented certain new and useful Improvements in Means for Reversing Internal-Combustion Engines, of which the following is a specification.

10 This invention relates to means for reversing two-stroke cycle internal combustion engines of duplex type, in which two cylinders side by side work as one unit, both inlet and exhaust (which belong to separate 15 cylinders) being usually controlled by the pistons. In such engines it is advantageous to arrange the cranks so that one piston, preferably the exhaust piston has a forward lead, an objection to such an arrangement, 20 however, lying in the fact that if the engine is simply reversed without other adjustments the various operations will occur in incorrect sequence.

According to this invention, when the direction of running is reversed the functions 25 of the two cylinders are interchanged, the inlet cylinder becoming the exhaust and vice versa, so that the piston lead remains correct for both directions of running. For 30 this purpose the supply pump, which may be mounted alongside the cylinders, is connected through a reversing valve to either of the cylinders at will, the position of the valve determining which cylinder is placed 35 in communication with the pump, that cylinder forming, of course, the inlet cylinder. Another valve controls the exhaust, opening either cylinder, according to the position of the inlet valve, to a common exhaust. 40 These valves are controlled simultaneously in any convenient manner, either by hand, or electrically, or by compressed air or other mechanical means.

In order that the said invention may be 45 clearly understood and readily carried into effect, it will be described more fully with reference to the accompanying drawings, in which:—

Figure 1 shows a diagrammatic section of 50 an engine of the type to which this invention relates, and Fig. 2 shows diagrammatically in section means for interchanging the functions of the cylinders according to this invention.

A, A are the two cylinders of the duplex 55 engine, the pistons *a* (see Fig. 1) of which are set one in advance of the other, either one of the cylinder ports *a'* serving for the inlet, while the second serves for the exhaust, according to the direction in which 60 the engine is driven. The ports *a'* are controlled by the pistons *a*.

B is the engine casing, C the pump cylinder mounted in the casing and D, D' are the reversing valves for admission and ex- 65 haust respectively.

Fig. 1 shows a double acting engine, but this is given merely as an example, the invention relating only to the reversing means.

Referring to Fig. 2, the valves D, D' slide 70 in the guiding channels *d* on opposite sides of the cylinders and control the inlet ports *a²* and the outlet ports *a³* respectively, either of the inlet ports *a²* being open to the 75 pump channel *c* for the supply of working fluid according to the position of the valve D, and either of the exhaust ports *a³* being correspondingly open to the common exhaust *b*. The ports *a²*, *a³* are of course independent of the piston controlled ports *a'*. The valves D, D' are connected to opposite ends of a lever *d'*, pivoted centrally at *d²*, so that the said valves move in opposite directions and when the inlet valve D closes 80 one cylinder to the pump, the exhaust valve D' opens the same cylinder to the exhaust *b* and closes the exhaust port *a³* of the other cylinder, with the result that the working fluid passes through either one of the cylinders to the second cylinder and thence, at 85 the end of the working stroke, to the exhaust through the cylinder port *a'* and main exhaust port *a³*. The lever *d'* is connected at *d²* to reversing mechanism or gear 90 of any suitable kind so that, simultaneously with the reversing of the direction of driving, there is an interchange of the functions 95 of the two cylinders, the former inlet cylinder becoming the exhaust cylinder, and vice versa. Owing to this interchange the various operations still occur in the correct sequence, the lead above referred to always being in the right sense for either 100 direction of driving.

What I claim and desire to secure by Letters Patent of the United States is:—

1. In a reversing duplex internal com-

bustion engine, two openly communicating working cylinders, means for connecting either cylinder to the inlet and the other to the exhaust, and means for interchanging said connections.

2. In a reversing duplex internal combustion engine, two openly communicating working cylinders, working pistons in the said cylinders of which one piston is given 10 a lead over the other, means for connecting either cylinder to the inlet and the other to the exhaust, and means for interchanging said connections.

3. In a reversing duplex internal combustion engine, two openly communicating working cylinders to either one of which the charge is admitted while the exhaust escapes from the other, a supply pump and an exhaust passage common to both cylinders, means for connecting the pump to 20 either one of the cylinders and the exhaust passage to the other, and interconnected sliding valves controlling the pump and exhaust connections to the cylinders, adapted on operation to interchange the said connections.

passage to the other, and means for interchanging said connections.

4. In a reversing duplex internal combustion engine, two openly communicating working cylinders to either one of which the charge is admitted while the exhaust escapes from the other, a supply pump and an exhaust passage common to both cylinders, means for connecting the pump to 25 either one of the cylinders and the exhaust passage to the other, and interconnected sliding valves controlling the pump and exhaust connections to the cylinders, adapted on operation to interchange the said connections.

In testimony whereof I affix my signature in presence of two witnesses.

ALAN ERNEST LEONARD CHORLTON.
